UNITED STATES PATENT OFFICE.

SAMUEL McMURRY, OF ALAMEDA, ASSIGNOR OF ONE-HALF TO EDWARD DONNELLY, OF SAN FRANCISCO, CALIFORNIA.

HYDROCARBON-BURNER.

SPECIFICATION forming part of Letters Patent No. 388,988, dated September 4, 1888.

Application filed September 16, 1887. Serial No. 219,883. (No model.)

To all whom it may concern:

Be it known that I, SAMUEL McMURRY, of Alameda, Alameda county, State of California, have invented an Improvement in Hydrocarbon-Burners; and I hereby declare the following to be a full, clear, and exact description of the same.

My invention relates to that class of devices for burning liquid hydrocarbon in which the parts are so arranged as to provide for a union of the hydrocarbon with air and steam, whereby it is atomized or vaporized; and my invention consists of such an arrangement of parts as will provide for the introduction and union, with the hydrocarbon in a heated state, of the air, also in a heated state, and superheated steam, all of which, together with details of construction, I shall hereinafter fully describe.

The object of my invention is to provide for the most complete and perfect atomizing or vaporizing of the liquid hydrocarbon, and this is attained by the union of the hydrocarbon and air, both in a heated state, with superheated steam.

Referring to the accompanying drawings for a more complete explanation of my invention, Figure 1 is a perspective view of my burner, showing it in position. Fig. 2 is a section of the burner.

In order to fully illustrate my burner, I have herein shown it in connection with a boiler, A, of which B is the fire-box.

The burner proper, which lies within the fire-box, consists of a pipe, C, shown in two sections, coupled at c, so as to leave an opening between them for the introduction of the air, as will presently be explained. One of the sections of the pipe C is coupled at c' to the oil-feeding device, which I shall hereinafter describe.

Around the forward section of the pipe C is fitted a pipe, D, having a diameter enough larger than the pipe C to leave an annular space between them, said space being closed at its forward end and having a coupling at d, where the pipe d' joins it, said pipe extending upwardly to the upper portion of the fire-box B for the purpose of drawing from said box the air which is heated to the highest temperature. The other end of the pipe is also closed, but has a pipe, d', connecting its inclosed space

with the space at c between the sections of the pipe C.

E is a pipe which extends through the pipe C to a point short of its forward end. The 55 pipe E has a diameter sufficiently small to leave a space between its outer surface and the inner surface of the pipe C, as shown, and the rear end of said pipe E is connected by a pipe, e, with the steam-boiler.

The means for feeding the oil, and which extends in front of the fire-box, consists of a pipe, F, connected at one end with the oil-reservoir (unnecessary herein to show) and at the other end at c' with the pipe C, the communication being controlled by a valve, f. The pipe F is provided with an enlargement forming a chamber, G, having a downward extension and an outlet controlled by a cock, g.

Around the rear of the pipe F is fitted a 70 larger pipe, H, providing for a space between itself and the pipe F, said space having a communication at h with a pipe, I, from the boiler, and an outlet controlled by a cock, i.

The operation of the burner is as follows: 75 The oil is first passed from the reservoir into the pipe F, wherein its temperature is raised by means of steam admitted from the boiler through the pipe I into the space inclosed by the pipe H, and the water of condensation 80 from said steam is drawn off through the cock i. The oil fills the enlarged chamber G of the pipe F, and the water which may be contained in it, sinking to the bottom of said chamber, is drawn off through the cock g. The oil now 85 passes, its flow being regulated by the valve f, into the pipe C of the burner, and flows forward in said pipe. Hot air is drawn from the upper portion of the fire-box down through the pipe d' and is admitted to the space inclosed by the pipe D of the burner, whence it 90 passes backwardly through the connecting-pipe d' and enters the pipe C, joining the oil in a highly-heated condition, and passes forward with said oil. Steam is admitted from 95 the boiler through the pipe e and passes into the pipe E, whence, blowing forward into said pipe, it is ejected from its forward end, meeting at that point and within the burner proper the heated air and heated oil. The oil is now 100 vaporized and atomized, and, being ignited, the burner itself soon becomes red hot and the

steam passing into it becomes superheated, so that the oil, the air, and the steam all operate under a high temperature. In this burner it will be seen that the discharge end is entirely open and untrammelled by any valve, so that heavy oils can be used with success, and the fact of bringing the air, the steam, and the oil together in a highly-heated condition adds to the usefulness of the burner in using all weights of oils.

Having thus described my invention, what I claim as new, and desire to secure by Letters Patent, is—

1. In a hydrocarbon-burner, the pipe C, for conveying oil and communicating at its rear end with the oil-supply, and the pipe E for steam, communicating with the boiler, said pipe being fitted within the pipe C and terminating short of its forward end, in combination with the pipe D, encircling the pipe C, the vertical pipe d' , communicating with the forward end of the pipe D, and a pipe, d^2 , con-

necting the rear end of the pipe D with the oil-pipe C at a point back of the forward end of the steam-pipe, substantially as herein described. 25

2. In a hydrocarbon-burner, the concentric pipes E, C, and D, for the steam, oil, and air, respectively, said pipes communicating, as described, in combination with the pipe F, for supplying oil to the pipe C, the chamber G in said pipe F, and the cock g , controlling said chamber, whereby the water in the oil is allowed to settle and may be drawn off, and the encircling steam-jacket H, having a cock, i , 30 whereby the water of condensation may be drawn off, substantially as herein described. 35

In witness whereof I have hereunto set my hand.

SAMUEL McMURRY.
